[57] CLAIM

The ornamental design for a motorized copy holder and line scanner, as shown and described.

DESCRIPTION

FIG. 1 is a front elevational view of a motorized copy holder and line scanner showing my new design;

FIG. 2 is a left side elevational view thereof;

FIG. 3 is a top plan view thereof;

FIG. 4 is a bottom plan view thereof;

FIG. 5 is a rear elevational view thereof; and,

FIG. 6 is a right side elevational view thereof.

The control button and cord are omitted from FIGS. 1 thru 5 and the cord is shown broken away in FIG. 6 for ease of illustration.

FIG. 1

FIG. 2

FIG. 3

FIG. 4

FIG. 5

FIG. 6
